UNITED STATES PATENT OFFICE

2,430,135

PULP WASHER

John Neumann, Chicago, Ill., assignor to Alpha Cellulose Corporation, Van Wert, Ohio, a corporation of Ohio

Application October 20, 1943, Serial No. 506,955

1 Claim. (Cl. 210—49.6)

1

This invention relates to pulp washers and its principal object is to provide a unit wherein paper pulp may be washed, cooked, bleached and rinsed. Another object is the provision of means for introducing wash water into the lower end of the unit together with an overflow opening at the top of the unit whereby the foreign matter contained in the pulp may be washed out of it and discharged through the overflow opening. Another object is the provision of separately controlled discharge outlets for liquid contained in the unit whereby certain liquids may be drained off into suitable receptacles for subsequent use and other liquids may be drained off and conducted away to the sewer or other place of disposal. Another object is the provision of a screen protected perforated false bottom for supporting the pulp and through which liquids may drain out of the pulp for future disposal. Another object is the provision of motor operated agitating means for agitating the pulp while being washed in the unit. Another object is to provide a screen at the overflow opening together with paddle means for agitating the waste liquid adjacent the screen so as to permit the free flow of overflow liquids therethrough. Another object is the provision of a valve controlled discharge outlet for the washed pulp and another object is the provision of a jacket through which a heating medium such as steam or hot water may be circulated to heat the contents of the unit. Another object is the provision of means for introducing steam or hot water into the interior of the tank whereby to cook the pulp. Another object is to perform the washing operation at atmospheric pressure.

With these and other objects and advantages in view, this invention consists in the several novel features hereinafter fully set forth and more particularly defined in the claim.

One embodiment of the invention is clearly illustrated in the accompanying drawings in which:

Figure 1 is a vertical axial section taken 45 through the apparatus;

Figure 2 is a horizontal section taken on the line 2—2 of Figure 1, and

Figure 3 is a detail cross section taken on the line 3—3 of Figure 1.

The type of stock ordinarily operated upon by the present washer is de-inked wastepaper stock which has been disintegrated, chemically treated and cooked, producing a cleansed pulp, all foreign materials going into solution ready to be

5 washed out of the stock. Such foreign materials may consist of clay, water-proofing, starch, glue, paraffin, grease, inks of all kinds, and other foreign substances. Colored paper should have all 10 of the color removed therefrom. All of these foreign materials must be washed out of the stock. The washer forming the subject matter of this specification is constructed and equipped so that it will wash all foreign materials from the pulp. This is done by putting a batch of treated, 15 cooked stock in the washing unit. Fresh wash water is let in at the bottom of the unit, rises therein and causes the waste liquid to overflow through a screen at the top of the unit which is kept free of the pulp by suitable paddle mechanism. The level of the stock in the unit is controlled by the flow of fresh wash water. The fibers are retained in the unit by a wire mesh screen based according to the requirements. The 20 stock is agitated in the unit to keep it in circulation as the fresh wash water rises from the bottom of the unit until it gradually forces out the waste liquor from the material so that after sufficient washing time the batch of stock is 25 thoroughly cleansed of all foreign matter.

Referring now to said drawings, which are merely illustrative of one embodiment of the invention, 10 designates a tank, preferably cylindrical, and having a concave bottom 11. Supported in the tank above the bottom 11 is a false bottom 12 which is provided with a multiplicity of perforations 13, throughout its area or throughout only a portion of its area. Soldered or otherwise secured to the upper face of the false bottom 12 is a wire mesh screen 14 which covers the perforations and prevents the fibers from escaping therethrough. Supporting rods or posts 15 are secured to the tank bottom 11 and support the false bottom 12.

Suitably spaced from the side wall and bottom wall of the tank is a jacket 15 for receiving a heating medium such as steam or hot water for supplying heat to the interior of the tank. A steam or hot water inlet pipe 16 opens to the space between the tank wall and jacket and an outlet pipe 17 leads away from this space. For supplying steam or hot water to the interior of the tank, a valve controlled supply pipe 18 is provided which opens to the interior of the tank.

The entire unit may be supported by supporting means such as legs 20 bolted or otherwise secured to the tank and connected by a ring-like member 21. A post 20a may be employed as a support at the center of the bottom. The jacket 15 and the

side wall and bottom wall of the tank may be held in spaced relation by suitable stay bolts 19 or otherwise as is well understood by persons skilled in the art to which this invention pertains.

The false bottom 12 is provided with a discharge opening 22 from which a discharge conduit 23 leads to the bottom wall 11 of the tank. The discharge conduit 23 may be flanged at its ends and the flanges may be welded to the false bottom and tank bottom or otherwise secured thereto as may be found desirable. A valve such as a slide valve 24 controls the passageway through the discharge conduit. The discharge conduit is shown as provided with a valve housing 25 into which the valve 24 may be slid when opening the passageway through the discharge conduit and means are provided for opening and closing said valve which means are shown as comprising rack teeth 26 provided upon the under face of the valve and meshing with pinions 27 carried by a shaft 28 journaled in suitable bearings and extending to the side of the tank where it is provided with a hand wheel 29 for its manipulation. The valve 24 slides in ways 30 formed on the discharge conduit. Discharge openings are provided in the tank bottom and jacket below the discharge conduit, and a threaded nipple 23a may be welded to the jacket around the discharge opening, to which a discharge pipe may be attached. A ring-like spacer 23b may be interposed between the tank bottom and jacket around the discharge openings and welded to the tank bottom and jacket.

The upper end of the tank 10 is open so as to permit liquids to overflow its upper edge, and extending upward from said upper edge is a screen or strainer 31 of suitable mesh which holds back any pulp that might otherwise overflow with the liquids. The screen may be conical or cylindrical and is secured to the tank in any desirable manner and it is here shown as formed with a downwardly projecting flange 41 secured between the inner face of the tank and a ring-like member 42 riveted or otherwise secured to the tank wall. A reinforcement ring 31a is secured to the upper edge of the screen.

Rotatable paddle means 32 are provided for clearing the inner face of the screen of any pulp that might collect thereon and said paddle means is shown as comprising a paddle-carrying ring 32a provided with radial spokes 33 that project from a hub 34 which is fixedly mounted upon an agitator shaft 35. Spaced around the ring-like member 32a is a plurality of paddles 36 which nearly contact with the inner face of the screen and are secured to the ring as by brackets 37. Secured to the wall of the tank slightly below its upper end is an annular gutter 38 into which the overflow liquid from the tank falls and is conducted away by a discharge pipe 39. The gutter 38 may be provided with a downwardly extending annular flange 40 riveted or otherwise secured to the wall of the tank.

The agitator shaft 35 extends vertically through the axis of the tank and its lower end is journaled in a thrust bearing 58 mounted upon a bearing bracket 59 welded or otherwise secured to the bottom wall 11 of the tank. The upper end of the agitator shaft is journaled in a bearing 60 carried by the framework of the unit. This framework may conveniently comprise oppositely disposed bracket plates 43 secured to the side wall of the jacket 15 as by angle irons 44 bolted or otherwise rigidly fastened thereto, upright posts 45 rigidly connected with the bracket plates

43 and channel bar members 46 rigidly secured to the upper ends of the posts. A platform 47 is secured to the upper sides of the channel bar members 46 and furnishes the support for the motor 48 and its speed reducing gearing 49 which is coupled to the agitator shaft 35.

Extending radially from the agitator shaft is an agitator which comprises agitator arms 50 that terminate at places adjacent the inner face of the tank wall 10. The agitator arms 50 are disposed one above the other along the length of the agitator shaft and the arms in each plane are arranged equidistantly in groups and are secured to a hub 51 which is rigidly mounted upon the agitator shaft.

Riveted or otherwise rigidly secured to the outer ends of the agitator arms 50 are spirally arranged conveyer bars 52 that act to circulate the contents in an upward direction as the bars are rotated through the tank. Intermediate the agitator arms 50 are shorter agitator arms 50a which are rigidly secured to hubs 51a mounted on the agitator shaft. The shorter agitating arms 50a are disposed in vertical planes intermediate the vertical planes of the longer agitating arms 50 as is clearly seen in Figure 2.

The bottom of the tank is formed with inlet openings 53, 54 from which lead valve controlled liquid supply pipes 53a, 54a, and the bottom is also formed with discharge openings 55, 56 from which lead valve controlled discharge pipes 55a, 56a.

In the operation of the pulp washer, a quantity of wash water is admitted through either or both of the supply pipes 53a, 54a, and rises through the perforations 13 in the false bottom and enters the main chamber of the tank. A batch of the material to be operated is then charged through the open top of the tank and allowed to stand for a short while, after which the valve of one of the discharge pipes 55a, or 56a is opened permitting the dirty water to drain out through the perforations in the false bottom and be discharged through the open discharge pipe. By permitting the dirty water to drain out of the tank before the washing operation begins, there is quite a saving of power and wear and tear on the mechanism, and hastens the washing operation. After the dirty water has been discharged, the valve of the open discharge pipe is closed and the valve of one of the supply pipes 53a, 54a is opened thereby admitting wash water to the main chamber of the tank which rises therein to the top thereof and overflows through the screen 31 into the gutter 38. The motor is started and it rotates the agitator shaft and therewith the agitator arms and the spiral bars 52 thereby agitating the mass, during which time wash water is being continuously supplied thereto and rises through the mass carrying with it the foreign materials and overflowing through the screen 31 into the gutter 38. Simultaneously, the paddle means is rotated by the agitator shaft and any pulp particles that may collect on the inner face of the screen are dislodged therefrom, thus keeping the screen free and clear for the passage of the waste liquid.

When the washing operation has been completed, the wash water supply pipe is shut off and one of the discharge pipes is opened, thereby permitting the liquid to drain out of the main chamber of the tank and during the draining operation the agitator is kept in motion so that the lowermost agitator arms may stir the pulp lying

on the false bottom and thereby prevent clogging of the screen.

After as much of the water has been drained off as will leave the pulp of the consistency required in manufacturing certain grades of paper, the valve of the open discharge pipe is closed and the valve 24 is opened, permitting the washed pulp to be discharged from the tank into suitable receptacles provided therefor.

If heat is required in the washing operation, steam or hot water is admitted to the jacket 15 through the supply pipe 16 and if it is desired to cook the pulp, steam may be admitted through supply pipe 18 to the interior of the tank.

Furthermore, one of the supply pipes 53a or 54a may lead from a tank containing a bleaching solution and when it is desired to bleach the pulp, the valve of the pipe leading from said bleaching solution tank is opened thereby admitting bleaching solution into the tank. When the bleaching operation has been completed, the valve of said supply pipe is closed and the valve of one of the discharge pipes 55a, 56a is opened to drain off the bleaching solution and this pipe may lead to a tank into which the bleaching solution may be discharged for further use. After the bleaching operation, the wash water pipe 53a or 54a is opened to the tank thereby admitting fresh clear water in an upward direction to the pulp whereby it may be thoroughly rinsed. The agitator may be kept in motion during all of these operations if necessary.

Having thus described the present invention, it is obvious that various immaterial modifications may be made without departing from the breadth and scope of the present invention. Therefore, no limitations should be placed on the exact form, construction, arrangement and combination of parts herein shown and described or to the uses mentioned excepting as shall be determined by the breadth and scope of the appended claim.

What I claim as new and desire to secure by Letters Patent is:

5 In a pulp washer and in combination, a tank open at its upper end and having a concave bottom, a liquid supply pipe opening through said bottom, a perforated false bottom above the concave bottom, a screen upon said false bottom, a valve controlled discharge pipe opening from said concave bottom, and a valve controlled pulp discharge outlet opening from said false bottom and extending through the concave bottom, a conical screen secured to the wall at its top and extending up therefrom, rotatory paddle means having paddles disposed adjacent the conical screen, means for rotating the paddle means, and a gutter disposed about the tank wall below the conical screen into which waste liquid overflows from the tank.

10 JOHN NEUMANN.
